The ornamental design for a vehicle steering wheel display screen with an animated graphical user interface, as shown and described.

DESCRIPTION

FIG. 1 is a front view of a vehicle steering wheel with a display screen with an animated graphical user interface showing a first image in the sequence showing our new design; and,

FIG. 2 is a second image thereof.

The broken line showing the vehicle steering wheel is for the purpose of illustrating environmental structure and forms no part of the claimed design. The appearance of the animated images sequentially transitions between the images of FIGS. 1 and 2. The process or period in which one image transitions to another forms no part of the claimed design.
